(57) **CLAIM**

The ornamental design for an on board diagnostics vehicle information system, as shown and described.

DESCRIPTION

FIG. 1 is a top view of an on board diagnostics vehicle information system of the instant invention;

FIG. 2 is a bottom view thereof;

FIG. 3 is a left view thereof;

FIG. 4 is a right view thereof;

FIG. 5 is a front view thereof;

FIG. 6 is a rear view thereof;

FIG. 7 is a top front perspective view thereof; and,

FIG. 8 is a top rear perspective view thereof.

The broken lines are for illustrative purposes only and form no part of the claimed design.
